UNITED STATES PATENT OFFICE.

HARRY W. BOLENS, OF PORT WASHINGTON, WISCONSIN, ASSIGNOR TO GILSON MANUFACTURING COMPANY, OF PORT WASHINGTON, WISCONSIN, A CORPORATION OF WISCONSIN.

ADJUSTMENT FOR TILTING-CHAIRS.

1,217,268.

Specification of Letters Patent. Patented Feb. 27, 1917.

Application filed June 16, 1915, Serial No. 34,412. Renewed January 22, 1917. Serial No. 143,844.

To all whom it may concern:

Be it known that I, HARRY W. BOLENS, a citizen of the United States, residing at Port Washington, in the county of Ozaukee 5 and State of Wisconsin, have invented a new and useful Adjustment for Tilting-Chairs, of which the following is a specification.

My invention relates to improvements in 10 tilting-chairs, and has particular reference to a new and improved adjustment for the same—that is, for raising and lowering the chair-supporting mechanism.

The principal objects of the invention are 15 to avoid wear, and thus increase the life of the adjustment, by substituting for the well-known threaded adjusting-post, designed to raise and lower in a threaded socket located in the chair-base, a fixed post, and mount 20 upon the same for vertical adjustment the chair carrying-means or mechanism; and, furthermore, to reduce the cost of the adjustment by a simplification and reduction 25 in the number of the parts composing the same, and yet at the same time sacrifice none of the convenient features thereof whereby the chair-seat may be readily raised and lowered.

Other, though minor objects, of the invention 30 will hereinafter appear, and the novel features of the invention will be particularly pointed out in the appended claims.

Referring to the drawing—

Figure 1 is a vertical, central, sectional view 35 of a portion of a chair-base carrying an adjustment constructed in accordance with my invention, parts being shown in elevation; and,

Fig. 2 is a horizontal cross-sectional view 40 on the line 2—2 of Fig. 1; while,

Fig. 3 is a detail in inverted plan of the washer.

Similar numerals of reference indicate 45 similar parts in all the figures of the drawing.

The chair-base 1, is of the conventional form, and has let into its upper side and at its center, the metal bushing 2, at the upper end of which occurs the circular flange 3.

Within the bushing, in the present instance, is secured by a set-screw 4, the non-rotatable rigid adjusting-post 5, which extends above the bushing a suitable distance and is threaded. The inner end of the set-screw 4 may simply impinge against the ad-

justing-post 5, or, as shown, the post may be provided with a small countersink or opening 5^a, for this purpose. In fact, the manner of supporting the adjusting-post may be varied at will, as such means form 60 no part of the invention, the only object being to mount the same in the base in such manner as to prevent all movement therein and thus do away with the usual wear and consequent looseness.

Threaded upon the adjusting-post, is the hub 6, of an adjusting hand-wheel 7, the hub, of course, being thickened, as shown, so as to afford a sufficiently long bearing on the adjusting-post to reduce wear to a 70 minimum and lend rigidity. Formed integrally upon the upper side of this hub, and surrounding the threaded central opening therein, is a vertical annular flange 8, the upper edge of which is preferably flared 75 outward whereby to form a peripheral lateral flange or bead 9. By forming the flange 8, there is produced an annular socket 10, in the upper side of the hand-wheel 7 and immediately surrounding the upper 80 threaded portion of the adjusting-post 5.

Within this socket 10, there is neatly yet movably fitted a washer 15, (see detail Fig. 3) and the inner edge of the opening thereof is formed with a lug 18. The washer-opening is unthreaded and is of a diameter to receive the adjusting-post 5, which latter is formed with a longitudinal groove 5^b, to receive the lug 18, whereby, as will be obvious, the washer is locked against rotation 90 but yet is free to slide vertically upon the post. The underside of the washer may be provided with a plurality of radiating preferably rounded ribs 17, the same being designed to temporarily engage with corresponding shallow grooves 16, formed in the bottom of the socket 10, whereby, under ordinary conditions, the hand-wheel and the washer are locked.

Above the washer may be located any desired form or construction of stretcher supporting yoke 11, the one herein shown, being of the conventional pattern, since, such is immaterial to my invention. In this instance, however, the yoke is provided with 105 a central unthreaded opening of a diameter sufficient to snugly receive the adjusting-post, as indicated at 12, and from one side of the yoke there depends a lug 14, which terminates below the peripheral flange or 110

bead 9 of the hand-wheel, and is provided with a threaded perforation coincident with the underside of said flange or bead, to receive a screw 13, which, under working conditions, is so adjusted that its inner end engages the said peripheral flange or bead, whereby the yoke and parts carried thereby become locked together and accidental separation of the chair-iron as a whole cannot occur.

10 The underside or lower end of the yoke rests, preferably, upon the upper side of the washer 15, the lower end of the yoke, therefore, not exceeding the diameter of the washer. If desired, as will be perfectly obvious, any ordinary anti-friction devices may be interposed between the lower end of the yoke and the upper side of the washer, but such are not believed to be necessary and, hence, are not shown. If preferred, the yoke may rest on the flange 9.

15 The operation of the invention will be readily apparent, it being seen that any vertical adjustment may be obtained by simply rotating the hand-wheel 7 so that the same will be fed up or down upon the threaded adjusting-post 5. During such operation, the ribs 17 and recesses 16 of the washer and hand-wheel, respectively, will readily disconnect, such being necessary in the present 20 instance wherein these parts are shown as temporarily locked together, the washer being fed up or down, in accordance with the direction of rotation of the hand-wheel, and with it, so also, is the yoke and the stretcher and other parts carried by the same, including the chair-seat.

25 The parts composing the adjustment, it will be seen, are comparatively few, and may be made sufficiently heavy and strong to endure continued and long service. The device is readily manipulated and the hand-wheel thereof is immediately locked by the immovable or non-rotatable washer in any 30 position it occupies upon release. Finally, the undesirable looseness occurring after use between the adjusting-post and chair-base is eliminated, the leverage, caused by the weight of the person occupying the chair, being transferred from the lower to the upper end of the screw, and being shortened, is thereby reduced to a very great degree.

35 Having described my invention, what I claim, is:

40 1. In a tilting-chair, the combination of a base, a fixed adjusting-post rising therefrom and rigid therewith and provided above the base with threads and a longitudinal groove, a hand-wheel threaded on the post, a washer encircling the post above the wheel and having a lug engaging the groove in the post, and a stretcher-yoke having an opening receiving the post and rotatable and adjustable thereon, and seated on the washer.

45 2. In a tilting-chair, the combination of a

base, a fixed adjusting-post rising therefrom and rigid therewith and provided above the base with threads and a longitudinal groove, a hand-wheel threaded on the post, a washer encircling the post above the wheel, means for temporarily locking the two together in a detachable manner, said washer having an internal lug engaging slidably with the groove in the post, and a stretcher-yoke having an opening receiving the post and rotatable and adjustable thereon, and seated on the washer.

50 3. In a tilting-chair, the combination of a base, a fixed adjusting-post rising therefrom and rigid therewith and provided above the base with threads and a longitudinal groove, a hand-wheel threaded on the post, a washer encircling the post above the wheel, means for temporarily locking the two together in a detachable manner, said washer having an internal lug engaging slidably with the groove in the post, a stretcher-yoke having an opening receiving the post and rotatable and adjustable thereon, and seated on the washer, and means for locking the stretcher-yoke and the hand-wheel together whereby to permit of independent rotation yet prevent longitudinal separation.

55 4. In a tilting-chair, the combination of a base, an adjusting-post rising therefrom and provided with threads and a longitudinal groove, a hand-wheel threaded on the post, a washer encircling the post and having a lug engaging the groove of the post, means for temporarily and detachably locking the washer and hand-wheel together, and a stretcher swiveled on the post and vertically adjustable by the hand-wheel.

60 5. In a tilting-chair, the combination of a base, an adjusting-post rising therefrom and provided with threads and a longitudinal groove, a hand-wheel threaded on the post, a washer encircling the post and having a lug engaging the groove of the post, removably interlocking lugs and grooves formed on the meeting faces of the hand-wheel and washer, and a stretcher swiveled on the post and vertically adjustable by the hand-wheel.

65 6. In a tilting-chair, the combination of a base, an adjusting-post rising therefrom and provided with threads and a longitudinal groove, a hand-wheel threaded on the post and provided on its upper side with radial shallow grooves, a washer encircling the post above the hand-wheel and engaging the groove of the post and provided on its underside with ribs removably engaging the grooves of the hand-wheel, and a stretcher swiveled on the post and vertically adjustable by the hand-wheel.

7. In a tilting-chair, the combination of a base, an adjusting-post rising therefrom and provided with threads and a longitudinal groove, a hand-wheel threaded on the post, a washer encircling the post and having a

- lug engaging the groove of the post, said washer being located above the hand-wheel, means for removably locking the washer and hand-wheel together, and a stretcher 5 swiveled on the post and supported by the washer.
8. In a tilting-chair, the combination of a base, an adjusting-post rising therefrom and provided with threads and a longitudinal 10 groove, a hand-wheel threaded on the post, a washer encircling the post, and engaging the groove of the post, means for removably locking the washer and hand-wheel together, a stretcher swiveled on the post and adjustable by the hand-wheel, and means for removably engaging the hand-wheel with the 15 stretcher whereby they are locked against vertical separation and yet capable of independent rotation.
9. In a tilting-chair the combination of a base, a fixed adjusting-post rising therefrom and provided above the base with threads and a longitudinal groove, a hand-wheel 20 threaded on the post and having on its upper side an annular flange forming an annular recess about the post, the bottom of 25
- the recess having radiating shallow grooves and the upper edge of the flange having a peripheral surrounding bead, a circular washer fitting loosely within the recess and 30 provided with an internal lug engaging the longitudinal groove of the post and upon its underside with shallow ribs corresponding to and removably engaging the grooves of the hand-wheel, a stretcher-carrying yoke 35 loosely mounted on the post above the hand-wheel and washer and free to rotate and vertically adjustable on the post through the rotations of the hand-wheel, a lug depending from the yoke below the peripheral rib 40 of the flange of the washer and provided with a threaded perforation, and a screw threaded in the perforation and at its inner end engaging under the said peripheral rib. 45

In testimony whereof I have signed my name to this specification in the presence of two subscribing witnesses.

HARRY W. BOLENS.
